UNITED STATES PATENT OFFICE.

JOHAN A. ZINN, OF PHILADELPHIA, PENNSYLVANIA, ASSIGNOR TO
BEMENT, MILES & CO., OF SAME PLACE.

HYDRAULIC VALVE.

SPECIFICATION forming part of Letters Patent No. 569,907, dated October 20, 1896.

Application filed September 24, 1895. Serial No. 563,542. (No model.)

To all whom it may concern:

Be it known that I, JOHAN A. ZINN, a citizen of the United States, residing in Philadelphia, Pennsylvania, have invented certain 5 Improvements in Hydraulic Valves, of which the following is a specification.

The object of my invention is to simplify the construction of hydraulic valves, so that many of the parts may be in duplicate; and 10 a further object of my invention is to provide a valve in which all the packing is seated within the casing. These objects I attain in the following manner, reference being had to the accompanying drawings, in which—

15 Figure 1 is a side view of my improved hydraulic valve, and Fig. 2 is a sectional view.

A is the casing, having the inlet-port a , the exhaust-port a^2 , and the port a' to the machine to be operated.

20 A' is the supply-chamber.

A^2 is a chamber communicating with the port leading to the machine through the passage a^3 , and A^3 is a chamber communicating with the exhaust-chamber A^4 . This chamber 25 communicates with the port a' through the exhaust-passage a^4 .

B is the piston-valve, having ports b b' , which form a communication between the chambers A' and A^2 , and the ports b^2 and b^3 , 30 which form a communication between the chambers A^3 and A^4 .

Adapted to a curved seat c in the casing A is a packing-ring e , U-shaped in cross-section, and pressing down upon this ring is a metallic follower-ring I, having a tongue i , adapted 35 to the U-shaped packing e . Mounted above this ring I is a sleeve E, perforated to allow for the passage of the fluid into the valve, and this sleeve supports the ring I', being a 40 duplicate of the ring I. This ring has a tongue i' , which forces the packing e' into a socket f , formed on the lower portion of the cage F. The upper end of this cage has a tongue f' , which forces the packing-ring e^2

45 into the seat formed in the cap C of the valve. The cage F is screw-threaded and is adapted to the screw-threaded opening in the cap.

Between the cap C and the valve-casing A is a packing-ring c' , and the cap is held in

place by nuts d d' , adapted to threaded bolts d' , projecting from the casing.

Seated in the lower portion of the valve is a ring I^2 , similar to the ring I, and this ring has a tongue i^2 , adapted to force the packing e^3 into the seat f^2 of the cage F' , which is a 55 duplicate of the cage F, and has a tongue f^3 , which confines the packing e^4 against the seat formed in the cap C' , which is held in place by screw-bolts and nuts similar to the cap C.

The cages F and F' are screwed into their 60 respective caps C C' , and the packing e^2 and e^4 are thus confined in place. The other packing-rings are then adjusted in the casing and the caps applied. Thus it will be seen that by screwing down upon the cap C the 65 packing-rings e and e' are tightened, and by screwing upon the cap C' the ring e^3 is tightened; and, further, it will be noticed that the caps C C' are duplicates, as well as the cages F F' and the rings I I' I^2 . All the packing- 70 rings are alike. Consequently the valve can be made very cheaply and of few parts. Suitable nipples are provided for the supply-port a and for the port to the machine, a' , and the exhaust-port is coupled to the exhaust-pipe 75 in the ordinary manner.

When the valve is in the position shown in Fig. 2, it will cut off fluid under pressure from the machine; but the exhaust is open from the machine, allowing the fluid to escape; but when the valve is raised so as to bring the port b up into the chamber A^2 the fluid under pressure will pass from the chamber A' into the chamber A^2 , through the passage a^3 to the machine, and both ports b^2 and b^3 85 will be in the chamber A^3 , and consequently the exhaust-port will be cut off from the machine.

The valve is operated by a handled lever B' in the usual manner, though it will be understood that it may be operated in any manner without departing from my invention.

By the above-described arrangement the packing-rings, which are preferably of leather, 95 are not exposed to the action of the fluid, except as the valve-stem is shifted. Then the pressure of fluid entering the ports of the

valve-stem keeps the packing in place and clear of the ports, thus preventing wearing of the packing.

I claim as my invention—

- 5 1. The combination in a hydraulic valve, of the casing having supply and exhaust ports and a port to the machine, and having chambers therein, the chamber A' communicating with the supply-port, the chambers A² and A³ communicating with the port to the machine, and the chamber A⁴ communicating with the exhaust-port, packing between the chambers, a piston-valve having two sets of ports, one set forming communication between the chambers A' and A², and the other set forming communication between the chambers A³ and A⁴, substantially as specified.
- 10 2. The combination in a hydraulic valve, of the casing having chambers A', A², A³ and A⁴ formed therein, caps adapted to each end of the casing, packing-rings in the caps, cages, follower-rings and packing between the chambers, with a piston having ports therein, substantially as described.
- 15 3. The combination in a hydraulic valve, of the casing having the chamber A' communicating with a supply-port, chambers A² and A³ communicating with a port to the machine and an exhaust-chamber A⁴, packing-

rings e, e' and e³, tongued followers i, i', i² 30 adapted to the packing-rings, cages F, F', and caps, substantially as described.

4. The combination of the casing A having the chambers A', A², A³ and A⁴, a packing-ring e adapted to the seat in the casing, a 35 follower i mounted on the ring, a sleeve E and a follower i' mounted on the sleeve, a packing e', a cage F adapted to receive the packing e', a cap C to which the cage is 40 adapted, a ring I² adapted to the opposite end of the casing, a packing-ring e³ adapted to said ring, a cage F', packing e⁴, a cap C', with a piston-valve B having two sets of ports arranged substantially as described. 45

5. The combination in a hydraulic valve, of the casing, the piston-valve, ports therein, a cap for the casing, a cage screwed into the said cap, a packing-ring confined in the cap by the cage, said cage also confining a packing in the casing, substantially as described. 50

In testimony whereof I have signed my name to this specification in the presence of two subscribing witnesses.

JOHAN A. ZINN.
